ABSTRACT OF THE DISCLOSURE

This invention relates generally to a molten metal producing furnace and more particularly to an improved furnace for producing molten iron for use in a basic oxygen furnace. A basic oxygen furnace is provided with exhaust outlet means for exhaust gases from the basic oxygen furnace. A molten metal producing furnace is disposed adjacent the basic oxygen furnace and adapted to receive a molten metal producing material, and a conduit means is connected to the exhaust outlet means and the molten metal producing furnace, the exhaust gases being operable to melt the molten metal producing material into molten metal. The conduit is operable to selectively engage either the exhaust outlet means or a fluid control means which can provide heated fluids to the conduit and thence to the molten metal producing furnace when the basic oxygen furnace is not producing exhaust gases.

Heretofore basic oxygen furnaces have been of the type shown in the following U.S. patents:

U.S. Patents Nos. 2,644,746, H. Hautmann, July 7, 1953; 2,741,554, R. F. Rinesch, Apr. 10, 1956; 2,741,555, O. Cuscoleca et al., Apr. 10, 1956; 2,789,046, K. G. A conventional basic oxygen furnace is first charged with light scrap and heavy scrap and finally with molten pig iron. This molten pig iron is necessarily produced primarily in a blast furnace or, in the case of a nonintegrated steel plant, in a cupola of the type described in the July 1964 issue of "Iron and Steel Engineer" on pages 189-192. One disadvantage of a conventional basic oxygen furnace is the need for the auxiliary blast furnace and/or cupola.

After the charging of the basic oxygen furnace has been completed, the oxygen lance is lowered into the basic oxygen furnace and the "blow" commences, thereby developing temperatures around 4000° F. and an excess of 300,000,000 B.t.u./hr. This developed heat is dissipated through a water-cooled hood on the basic oxygen furnace, which hood requires auxiliary cooling apparatus, such as high-powered pumps, cooling towers and a steam-expansion chamber provided with relief valves. From the above description it will be appreciated that other defects

associated with conventional basic oxygen furnaces are the dissipation of the heat developed in the basic oxygen furnace, the requirement for expensive auxiliary cooling apparatus and the attendant high operating cost of the conventional basic oxygen furnace.

The general object of the present invention is to avoid and overcome the foregoing and other difficulties of and objections to prior art practices by the provision of an improved furnace for producing molten metal and a fluid control assembly therefor, which furnace and control assembly therefor:

- (1) Eliminate the need for a blast furnace and/or cupola for a basic oxygen furnace;
- (2) Substantially utilize and substantially eliminate the dissipation of the large quantity of heat generated in such basic oxygen furnace;
- (3) Partially eliminate the water-cooled hood and related cooling apparatus normally associated with a basic oxygen furnace; and
- (4) Substantially reduce the operating costs associated with a basic oxygen furnace.

The aforesaid objects of the present invention, and other objects which will become apparent as the description proceeds, are achieved by providing a basic oxygen furnace provided with exhaust outlet means for the exhaust gases from the basic oxygen furnace and a molten metal producing furnace disposed adjacent the basic oxygen furnace and adapted to receive a molten metal producing material. A conduit means connects the exhaust outlet means and the molten metal producing furnace. The exhaust gases are operable to melt the molten metal producing material into molten metal. The fluid control assembly has a sealing member in engagement with the conduit means and fluid control means adjacent the sealing member for controlling the flow of fluid through the conduit means.

For a better understanding of the present invention, reference should be had to the accompanying drawings wherein like numerals of reference indicate similar parts throughout the several views and wherein:

FIGURE 1 is a side elevational view of the improved molten metal producing furnace and the associated basic oxygen furnace;

FIGURE 2 is a vertical sectional view taken along the line II—II of FIGURE 1 in the direction of the arrows showing the interior of the molten metal producing furnace;

FIGURE 3 is a vertical sectional view taken along the line III—III of FIGURE 1 in the direction of the arrows showing the batching bin, swivel hood and conduit means disposed between the batching bin and the swivel hood;

FIGURE 4 is an enlarged fragmentary side elevational view partially in section of the swivel hood and fluid control assembly;

FIGURE 5 is a horizontal sectional view taken along the line V—V of FIGURE 4 in the direction of the arrows;

FIGURE 6 is a fragmentary side elevational view partially in section of a basic oxygen furnace having a rotatable vessel;

FIGURE 7 is a fragmentary view similar to FIGURE 1 showing an alternative embodiment of the molten metal producing furnace and two basic oxygen furnaces; and

FIGURE 8 is a plan view of the molten metal producing furnace and basic oxygen furnaces shown in FIGURE 7.

Although the principles of the present invention are broadly applicable to a molten metal producing furnace, the present invention is particularly adapted for use in conjunction with a molten scrap iron producing furnace and hence it has been so illustrated and thus been so described.

With specific reference to the form of the present invention illustrated in the drawings and referring particularly to FIGURES 1 and 2, a basic oxygen furnace is indicated generally by reference numeral 10.

As shown in FIGURE 1, this basic oxygen furnace 10 is provided with exhaust outlet means, such as the mouth 12, for the exhaust gases. Such basic oxygen furnace 10 is pivotally mounted on bearings 14 mounted on supporting piers 16 and is oscillatable on the bearings 14 by a drive means, such as the gear reduction unit 18 and motor 20.

After the basic oxygen furnace 10 is charged while in the tilted position (not shown in FIGURE 1) with scrap metal from a charging box (not shown) and with molten pig iron from a hot metal ladle (not shown), an oxygen lance 22 is lowered from an oxygen lance frame 24 through a combination guide and heat seal 26 in a swivel hood 28 (FIGURES 1, 3 and 4) into the basic oxygen furnace 10 to a predetermined position above the surface of the bath by means of a hoist 30. The oxygen is then released from the oxygen lance 22, thus generating about 300,000,000 B.t.u./hr. and temperatures of about 4000° F. in the exhaust gases from the basic oxygen furnace 10. After the oxygen jet is released, slag forming fluxes, such as burned lime, fluospar and mill scale are added in controlled amounts from a batching bin 32 (FIGURES 1 and 3) through a chute 34 to the basic oxygen furnace 10. A piston 36 of a fluid operated cylinder 38 (FIGURE 3) operates an arm 40 connected at 42 to a door 44 and hence oscillates the door 44 between the left-hand dotted line open position shown in FIGURE 3 and the right-hand dotted line closed position shown in FIGURE 3.

A conduit or hood means, such as the swivel hood 28 (which swivels between its solid line position, FIGURE 1, and its dotted line position, FIGURE 1) and a fixed hood 46 (FIGURE 1), connects the mouth 12 to an entrance aperture 48 (FIGURES 1 and 2) in a molten metal producing furnace, such as a scrap metal furnace 50, adapted to receive molten metal producing material, such as scrap metal and pig iron (hereinafter called scrap metal 52) or furnace additions, such as molybdenum, titanium, magnesium, nickel, iron ore and the like. The exhaust gases are operable by conduction, radiation and convection to melt such scrap metal 52 to molten scrap metal 54. Hot exhaust gases from the scrap metal furnace 50 exit through exhaust means, such as an exit aperture 56 (FIGURES 1 and 2) in the scrap metal furnace 50, scrap metal stack 58 and a gas stack 60.

It will be understood that the swivel hood 28, fixed hood 46, scrap metal furnace 50, scrap metal stack 58 and gas stack 60 are lined, for example, with a heat-resistant lining 62, such as a first or outer layer of burned magnesite brick, a second layer of basic ramming mix and a third or inner layer of unfired tar-bonded dolomite, dolomite-magnesite or magnesite bricks. The swivel hood 28 may be water cooled by means of conventional pipes, manifolds and connecting lines (not shown). As shown in FIGURE 1, control means, such as the damper 64, are disposed in gas stack 60 controlling the flow of exhaust gases through and the resultant temperature in the scrap metal furnace 50.

After the oxygen lance 22 (FIGURE 1) has been withdrawn from the basic oxygen furnace 10 and the basic oxygen furnace 10 has been tapped through tap hole 66 into a hot metal ladle 68, the basic oxygen furnace 10 is charged with scrap metal from a charging box (not shown). A tap hole 70 (FIGURES 1 and 2) in the bottom wall of the scrap metal furnace 50 is then opened, thereby permitting the molten scrap metal 54 to pour down supply means, such as a hot metal chute 72, into the now tilted basic oxygen furnace 10, which hot metal chute 72 is provided with a heat-resistant lining and preheated and additionally heated by conventional gas jets (not shown).

If weighing of the charge of molten scrap metal 54 from the scrap metal furnace 50 is required, the molten metal 52 from the hot metal chute 72 is directed to a con-

ventional hot metal ladle (not shown) supported on a scale (not shown), which hot metal ladle is then transferred by crane (not shown) to the tilted basic oxygen furnace 10.

Thereafter, the lance 22 is again lowered into the basic oxygen furnace 10, oxygen is released from the lance 22 and the slag forming fluxes are added to the basic oxygen furnace 10 from the batching bin 32 as explained above, thus initiating the next heat cycle.

As shown in FIGURE 1, feed means are connected to the scrap metal furnace 50 for introducing scrap metal 52 into the scrap metal furnace 50.

Feed means

For the purpose of charging the scrap metal furnace 50 (FIGURE 1) with scrap metal 52, such scrap metal 52 is dumped from a truck (not shown) into a scrap car 74 shown in the dotted line position of FIGURE 1. The now loaded scrap car 74 is then moved by drive means (such as a motor 76, drum 78, cable 80 and counterweight 82) up an inclined track 84 to its solid line position (FIGURE 1) and the scrap metal 52 is dumped through a now open pivotable entrance door 86 in a scrap metal chamber 88. The pivotable entrance door 86 is opened and closed by a hoist 90. When the scrap metal chamber 88 is filled, the entrance door 86 is closed and a slideable exit door 92 in the scrap metal chamber 88 is opened by a hoist 94, thus permitting the charge of scrap metal and pig iron 52 to gravitate down the scrap metal stack 58, and into the scrap metal furnace 50.

Alternative embodiments

It will be understood by those skilled in the art that alternatively that if, for example, it is essential to expedite the melting of the scrap metal 52 into molten scrap metal 54, oxygen lance means, such as an oxygen lance 96 (FIGURE 1) operable by a drum 98 may be lowered into the scrap metal furnace 50 to add oxygen to the melting scrap metal 54.

Further additional heat may be provided in the scrap metal furnace 50 by means of burner means, such as burners 100 (FIGURES 1 and 2).

Alternatively, a fluid control assembly 101 (FIGURES 1, 4 and 5) is used with the basic oxygen furnace 10. If, for example, the basic oxygen furnace 10 is not operating, the swivel hood 28 is rotated from the exhaust gas receiving position (the solid line position of FIGURE 1) to the fluid inlet control position (the dotted line position of FIGURE 1) by drive means (such as a girth gear 102 on the swivel hood 28 and a pinon gear 104 on the drive shaft of a motor 106). During such movement the swivel hood 28 slides on and is supported by an arcuate rail 108 (FIGURE 1). In the dotted line position shown in FIGURE 1, the swivel hood 28 engages a sealing member, such as an annular sealing plate 110 (FIGURES 4 and 5), mounted on guides 112. These guides 112 are reciprocable in frame means, such as H-beams 114, pistons 116 of fluid operated cylinders 118 (FIGURE 4).

As shown in FIGURE 4, mounting means, such as an open-ended annular frame 120, is mounted on ring 110. This frame 120 contains a fluid preheating means, blower means and fluid inlet control means. The fluid preheating means is by way of example a resistance type air heater 122 connected to a suitable voltage supply or a fluid-fired heat exchanger (not shown). The blower means is a fan 124 mounted on a shaft 126 of a motor 128. Disposed about the shaft 126 is a fixed louver 130 and a movable louver 132 of the fluid control assembly 101. The movable louver 132 is operable by hand or by a piston 134 of an adjustable fluid operated cylinder 136 to the desired position with respect to the fixed louver 132, thereby controlling the amount of a fluid, such as air, flowing into the swivel hood 28.

Thereafter, the scrap metal 52 (FIGURE 1) within the scrap metal furnace 50 is melted by either the burners

100 or the burners 100 and the oxygen from the oxygen lance 96.

In FIGURE 6, the basic oxygen furnace 10⁶ has a tiltable rotatable vessel 138 and a rotating mechanism 140 driven by a motor 142. The motor 142 drives pinion gears 144 of the rotating mechanism 140 which pinion gears 144 engage girth gears 146 on the vessel 138.

It will be understood that a rotor type basic oxygen furnace (not shown) having a kiln-like vessel may be employed. The kiln-like vessel of the rotor type basic oxygen furnace is rotatable by a rotating mechanism mounted on a base plate and tiltable by a semicircular tilting gear.

Referring now to FIGURES 7 and 8, the scrap metal furnace 50⁷ is provided with a molten scrap metal portion 50^{7a} and scrap metal melting portion 50^{7b}, which portions 50^{7a} and 50^{7b} are heated by basic oxygen furnaces 10^{7a}, 10^{7b}. The bottom of molten scrap metal portion 50^{7a} is sloped toward tap holes 70^{7a}, 70^{7b} and the scrap metal melting portion 50^{7b} is provided with a trough 148 in the bottom to carry molten scrap metal 54⁷ into molten scrap metal portion 50^{7a}. Alternatively, the basic oxygen furnaces 10^{7a}, 10^{7b} can also be connected to the fixed hoods 46^{7a}, 46^{7b} respectively to provide greater flexibility. Also, both basic oxygen furnaces 10^{7a}, 10^{7b} can be connected by a Y-connection (not shown) to the fixed hood 46^{7a} and the entrance aperture 48^{7b} blocked off (not shown).

It will be understood by those skilled in the art from the above description of the preferred and alternative embodiments of the present invention, that an improved method is provided.

Method

This method comprises the steps of introducing a molten metal producing material, such as the scrap metal 52, into a molten metal producing furnace, such as the scrap metal furnace 50, conducting the exhaust gases from the basic oxygen furnace 10 (FIGURES 1-4), 10⁶ (FIGURE 6), 10^{7a}, 10^{7b} (FIGURES 7 and 8) to the scrap metal furnace 50, etc. respectively, heating the molten metal producing material, such as the scrap metal 52, by means of the exhaust gases to melt the scrap metal 52 into molten scrap metal 54.

It will be recognized by those skilled in the art that the objects of the present invention have been achieved by providing an improved molten metal producing furnace and an improved method for producing molten metal which eliminates the need for a blast furnace and/or cupola for a basic oxygen furnace. Further, such improved apparatus and method substantially utilizes and substantially eliminates the dissipation of the large quantity of heat generated in the conventional basic oxygen furnace. Further, the improved apparatus and method substantially partially eliminates the water-cooled hood and related cooling apparatus normally associated with a basic oxygen furnace and substantially reduces the operating costs of such basic oxygen furnace.

While in accordance with the patent statutes, preferred and alternative embodiments have been illustrated and described in detail, it is to be particularly understood that the invention is not limited thereto or thereby.

I claim:

1. In combination:

- (a) a basic oxygen furnace provided with exhaust outlet means for exhaust gases from said basic oxygen furnace,
- (b) a molten metal producing furnace disposed adjacent said basic oxygen furnace and adapted to receive a molten metal producing material,
- (c) conduit means connecting said exhaust outlet means and said molten metal producing furnace so that said exhaust gases engage said molten metal producing material in said molten metal producing furnace in heat exchange engagement to melt said

molten metal producing material into molten metal, and

- (d) fluid control means adjacent said basic oxygen furnace,
  - (e) said conduit means having a swivel portion adjacent said exhaust outlet means and drive means connected to said swivel portion for moving said swivel portion between an exhaust gas receiving position adjacent said exhaust outlet means and a fluid inlet control position, adjacent said fluid control means where said swivel portion engages said fluid control means in sealing engagement.
  - (f) said fluid control means being operable to preheat a fluid and drive said preheated fluid through said conduit means and into said molten metal producing furnace when said swivel portion is in sealing engagement with said fluid control means.
2. The combination recited in claim 1 wherein said fluid control means has a sealing member engageable with said swivel portion and operating means connected to said sealing member for forcing said sealing member into sealing engagement with said swivel portion.
3. The combination recited in claim 1 wherein said fluid control means has fluid inlet control means for controlling the flow of said fluid through said conduit means.
4. The combination recited in claim 1 wherein said fluid control means has preheating means for preheating said fluid.
5. The combination recited in claim 1 wherein said fluid control means has blower means for driving said fluid through said conduit means and into said molten metal producing furnace.
6. The combination recited in claim 1 wherein said molten metal producing furnace is provided with exhaust means for said exhaust gases and has control means in said exhaust means for controlling the flow of said exhaust gases from said molten metal producing furnace through said exhaust means.

7. The combination recited in claim 1 and having supply means disposed between said basic oxygen furnace and said molten metal producing furnace for transferring molten metal from said molten metal producing furnace to said basic oxygen furnace.

8. The combination recited in claim 1 and having feed means connected to said molten metal producing furnace for introducing said molten metal producing material into said molten metal producing furnace.

9. The combination recited in claim 1 wherein said molten metal producing furnace has burner means for assisting the melting of said molten metal producing material.

10. The combination recited in claim 1 wherein said molten metal producing furnace has oxygen lance means for assisting the melting of said molten metal producing material.

11. The combination recited in claim 1 wherein said molten metal producing furnace has a metal melting portion and a molten metal portion in communication with said metal melting portion.

12. The combination recited in claim 11 wherein said conduit means is connected to said molten metal portion and having a second basic oxygen furnace provided with a second exhaust outlet means for exhaust gases from said second basic oxygen furnace and having a second conduit means connecting said second exhaust outlet means to said metal melting portion.

13. The combination recited in claim 11 wherein said conduit means is connected to said molten metal portion and having a second basic oxygen furnace provided with a second exhaust outlet means for exhaust gases from said second basic oxygen furnace and having a second conduit means connecting said second exhaust outlet means to said conduit means.
